Primary Examiner — Eric L Goodman*Assistant Examiner* — Sarah L Smith(74) *Attorney, Agent, or Firm* — Legalforce RAPC Worldwide**CLAIM**

The ornamental design for a lantern, as shown and described.

DESCRIPTION

FIG. 1 is a front left side perspective view for a lantern, showing my new design;

FIG. 2 is a front perspective view of FIG. 1 thereof;

FIG. 3 is a rear perspective view of FIG. 1 thereof;

FIG. 4 is a left side perspective view of FIG. 1 thereof;

FIG. 5 is a right side perspective view of FIG. 1 thereof;

FIG. 6 is a top plan view of FIG. 1 thereof; and,

FIG. 7 is a bottom plan view of FIG. 1 thereof.

The broken lines indicate unclaimed portions of the lantern and form no part of the claimed design.

1 Claim, 7 Drawing Sheets(56)
